DOOR FOR REFRIGERATOR CARS

Arthur F. O'Connor, Chicago, Ill., assignor to
Union Asbestos & Rubber Company, a corpora-
tion of Illinois

Application June 10, 1946, Serial No. 675,585

1 Claim. (Cl. 20—23)

1

This invention relates to doors for refrigerator cars and more particularly to supporting and operating mechanism for relatively thick insulated doors.

With increasing use of refrigerator cars on long continuous runs and at lower temperatures, it has become necessary to increase the insulating value of the car walls and doors. In many instances thicknesses of from seven to ten inches are used. To avoid restricting the size of the lading compartment the wall thickness has generally been added to the outside and this has resulted in bringing the total exterior width of the car very close to the maximum permitted by clearance limits, leaving very little space outside of the car for fixtures or fittings to hold and operate the door. At the same time, the increased door thickness has required a substantial horizontal movement of the door away from the car to clear the door opening.

It is one of the objects of the present invention to provide a door for refrigerator cars in which the fixtures and fittings supporting the door project a minimum distance beyond the car wall when the door is closed and yet which provide adequate movement of the door to clear the opening.

Another object is to provide a door slidably supported on tracks which are movable toward and away from a car wall. According to one feature the tracks are carried by levers pivoted on the car and can collapse against the side of the car to leave projections of minimum size.

Still another object is to provide a door which seals tightly against a door opening without requiring an accurate fit in the opening.

A further object is to provide a simple operating mechanism for moving the tracks and door toward and away from the car wall.

A still further object is to provide latching mechanism for holding the door securely and tightly in closed position and which can easily be released for opening the door.

The above and other objects and advantages of the invention will be more readily apparent from the following description when read in connection with the accompanying drawings, in which—

Figure 1 is a partial side elevation of a refrigerator car equipped with a door embodying the invention;

Fig. 2 is a partial section on the line 2—2 of Fig. 1;

Fig. 3 is a plan view of a latch plate;

Fig. 4 is a partial section on the line 4—4 of Fig. 1;

Fig. 5 is a section similar to Fig. 4 showing the track in extended position;

Figs. 6 and 7 are partial sections on the lines 6—6 and 7—7, respectively, of Fig. 1;

Fig. 8 is a section on the line 8—8 of Fig. 7; and

2

Fig. 9 is a partial section on the line 9—9 of Fig. 1.

The invention is illustrated in connection with a conventional refrigerator car having an insulated side wall 10 which may be of substantial thickness and which is formed centrally of its length with a door opening. As shown, the door opening is bounded by metal framework 11 which tapers inwardly of the car and which terminates substantially flush with the inner wall of the car.

The opening is adapted to be closed by a door panel 12 which may be insulated and which is of substantially the same thickness as the car side wall 10 so that when the door is closed its inner surface will lie flush with the inner wall of the car. The door panel may be made up of metal sheets or plates connected together with insulating material between them and preferably tapers inwardly to fit loosely within the frame 11. The outer panel of the door extends beyond the door outline as indicated at 13 to form a flange around the door which is adapted to fit against a resilient seal 14 carried by the car around the door opening. As shown, the seal 14 is in the form of a rubber U-shaped strip extending completely around the door frame 11 and normally projecting out a sufficient distance so that it will engage and be compressed by the flange 13 when the door is closed. In this way the door need not fit closely within the frame 11 and still an air-tight seal completely around the door will be formed by the sealing strip 14.

The door 12 is supported on an upper track 15 and a lower track 16 which extend along the car above and below the door opening therein. The lower track 16 is intended to support substantially all of the weight of the door and for this purpose the door carries grooved rollers 17 which rest on the track 16 so that the door can slide freely on the track. At its upper edge the door carries brackets 18 having upstanding parts 19 thereon which straddle the upper track 15 to prevent the door from swinging away from the car. Since the upper track carries none of the weight of the door and serves only to hold the door against the car, relatively light brackets, as shown at 19, will suffice.

In order to move the door toward and away from the opening, the tracks 15 and 16 are supported for movement toward and away from the car side wall. As best seen in Figs. 2, 4 and 5, the upper track has pins 21 secured thereto at spaced intervals which are journaled in bosses 22 carried at the ends of levers 23. The levers are pivoted to the car wall on vertical pivots 24 carried by brackets 25 which may be welded, riveted or otherwise permanently secured to the car wall. Any required number of levers may be provided to support the track properly. Since the upper track is not subjected to any substantial amount of weight, the levers 23 may be relatively light, as shown.

The lower track is similarly supported on a series of levers 26 which are generally triangular shaped and which are secured along one of their straight edges to the car body on spaced pivots 27 adjacent the upper and lower ends of the levers. It will be noted that the spacing between the pivots is substantially equal to the length of the levers so that the levers will be supported on a relatively long vertical axis. At their outer ends, the levers 26 carry bosses 28 which in turn rotatably receive pins 29 secured to the track 16. It will be noted that the levers 26 form the sole supports for the track 16. Ordinarily the levers are supported entirely by the pivots 27 so that when they are retracted against the car, as shown in Fig. 6, no parts of the mechanism project beyond the outer car wall a distance greater than the thickness of the lever pivots.

For moving the tracks toward and away from the car body, an elongated control shaft 31 is provided adjacent one end of the tracks and carries at its upper and lower ends short crank arms 32. The crank arms 32 are connected through links 33, as best seen in Fig. 8, to the central parts of the levers 23 and 26. Preferably, the lengths of the levers between their pivotal mountings to the links 33 are slightly greater than the lengths of the crank arms 32 to increase the mechanical advantage of the crank arms over the tracks and to provide a greater latch effect. With this construction, the crank arms move a distance greater than 90° to move the levers through a full 90° which results in maximum movement of the tracks toward and away from the car. An operating handle 34 is provided carried by a collar 35 loosely encircling the shaft 31 and having an enlarged notch therein receiving a projection on a collar 36 which is secured to the shaft 31. This construction provides a lost motion connection enabling the handle 34 to be swung through a full 180° while turning the shaft 31 and the crank arms 32 through the desired angle to swing the tracks. Latching devices 37 are provided on the door 12 and on the car side wall adjacent the door to hold the handle 34 in the desired position.

In order securely to latch the door closed when it is in its closed position, latch shafts 38 are provided extending vertically adjacent the opposite edges of the door with their ends projecting beyond the door. Latch plates 39 are secured to the car wall and are formed, as best seen in Fig. 3, with slots 41 sloping toward the car wall and opening at the outer edges of the plates 39 to receive the ends of the latch shafts 38. The shafts 38 are supported on the door by slotted brackets 42, as best seen in Fig. 9, which are formed along one side with rack teeth 43. The shafts 38 carry pinions 44 meshing with the rack teeth so that as the shafts are turned they will be moved laterally of their length to cause their ends to travel into the slots 41 from the dotted line to the full line position shown in Fig. 3. This will press the door firmly against its opening and will hold the door tightly closed during running.

The shaft 38 at the right of the door, as seen in Fig. 1, carries an operating handle 45 which may be latched to latch plates 46 secured to the door and to the car wall adjacent the right edge of the door. As the handle 45 is swung from the position shown to a position overlying the door, the shaft 38 at the right will be caused

to move to the left to move its ends toward the open ends of the slots 41 in its latch plates so that the door can be opened. Movement of the shaft 38 at the right is transmitted to the shaft 38 through connecting links 47 so that all of the latches will be simultaneously latched and released.

When the car is in use with the door closed the parts will occupy the position shown in Figs. 1, 2, 4 and 6 with the door firmly pressed into the door opening and the handles 34 and 45 latched in the positions shown. To open the door the handle 45 is first released and swung over against the door to release the latches. Thereafter the handle 34 is swung away from the door over the car wall to rock the levers 23 and 26 outward to move the tracks 15 and 16 away from the car wall. This operation moves the door out from the door opening to a position where it can be slid horizontally on the tracks out of register with the opening. For this purpose, the levers 23 and 26 are made slightly longer than the thickness of the door panel and car wall so that the door will clear the outer surface of the car wall.

It will be noted that when the door is in its closed position there are no parts projecting to any substantial distance beyond the outline of the car. Maximum insulation thickness with maximum lading capacity can thereby be provided within the permissible clearance limits.

While one embodiment of the invention has been shown and described in detail, it will be understood that this is illustrative only and is not intended to be taken as a definition of the scope of the invention, reference being had for this purpose to the appended claim.

What is claimed is:

A door for a refrigerator car having a relatively thick insulated wall formed with a door opening, comprising an insulated door panel of substantially the same thickness as the car wall adapted to fit into the opening, elongated tracks extending along the car wall above and below the door opening, means mounting the door on the tracks for sliding movement therealong into and out of register with the door opening, a plurality of horizontally spaced levers pivoted on vertical axes on the car supporting the tracks at their outer ends for swinging movement toward and away from the car wall and being of a length slightly greater than the thickness of the wall and the door panel, a vertical shaft rotatably mounted on a vertical axis adjacent one end of the tracks having laterally projecting crank arms thereon shorter than the levers, links connecting the cranks to points intermediate the lengths of upper and lower levers respectively, an operating handle on the shaft, and means forming a lost motion connection between the shaft and the operating handle.

ARTHUR F. O'CONNOR.
